P. VAN VLissingEN

PURGING DEVICE

Filed April 24, 1922

Peter Van Vlissingen,
By Offord Poole Hinton & Scott
2/25.

UNITED STATES PATENT OFFICE.

PETER VAN VLissingEN, OF CHICAGO, ILLINOIS.

PURGING DEVICE.

Application filed April 24, 1922. Serial No. 556,252.

To all whom it may concern:

Be it known that I, PETER VAN VLissingEN, a citizen of the United States, and a resident of Chicago, in the county of Cook and State of Illinois, have invented certain new and useful Improvements in Purging Devices, of which the following is a specification.

This invention relates to operation of mail order businesses and the like; and particularly to an improved means whereby the files may be accurately "purged" with great rapidity.

The invention will be better understood if a few preliminary considerations are recited. A mail order business is operated on a very small margin of profit for each transaction; the number of units involved in each routine operation is enormous. Operating costs are a vital factor in the business. Any reduction in the time involved in carrying out a normal step of operation, because multiplied by so many hundreds of thousands of times, effects very large aggregate annual saving. Furthermore, it is frequently and truly said that the success of a mail order business is dependent largely on the amount of its "complaint and adjustment" mail. It is estimated to cost 50 cents to handle every "complaint and adjustment" letter received. If every customer of a mail order house would write such a letter, say once a week, it might easily put the house out of business. Such mail is most effectively avoided by accuracy and promptness in transacting business.

The standard practice in operation of mail order business is to fold about each batch of papers relating to a transaction such as an order, a wrapper, upon which identifying and other records are entered—the wrapper passing around the upper edge of the batch of papers, and all being pinned together, then filed according to some classification scheme for ready reference as long as needed.

A large mail order business may receive one hundred thousand orders a day, each forming a separate file; it is evident that if these files were permitted to accumulate, they would overrun the establishment, and furthermore the time consumed in operation of finding a particular file, and the precision of that operation, is greatly affected by the number of files. Thus it is obviously more difficult to find a particular file among ten

thousand than among a thousand, and chances of deceptive duplication in identifying data are greatly increased in proportion to the number of files.

The invention facilitates "purging" whereby obsolete files are removed promptly and accurately, and the drawings present an illustrative embodiment thereof, in which—

Figure 1 is a perspective view of a drawer full of files,

Figure 2 is an elevation of one of the wrappers.

Figure 3 shows a set of "purging" designs.

The wrapper 1 (Figure 2) is folded over a sheaf of papers, the fold coming within the area indicated by the lines, 2—2. The wrapper bears spaces for stamps, inscription and other identifying data, as indicated at 3.

The wrapper and enclosed papers are pinned or otherwise fastened together and filed.

It is exceedingly important, for speed and accuracy in purging that the files to be removed be recognized infallibly and instantly, although so packed in drawers that only the top edge of the wrapper can be seen.

I provide wrappers (1) with a set (in this instance five) of conspicuous marks or "purging designs." These designs may be printed along with the other printed matter on the wrapper. They are so formed and arranged as to provide a distinctive, unmistakable and conspicuous mark, which extends across the fold in the wrapper, wherever that fold occurs, so that the mark may be seen and recognized in a packed drawer looked at from above; i. e., where only the upper edges of the files are visible. Each mark of the set is further designed with reference to the other marks, i. e., so as to reveal itself conspicuously, and distinctively, from each of the other marks of the set employed, even though only a small part thereof, at the upper edge of the file, is visible. Thus the marks form accurately a cooperative set or combination.

I regard the mutual distinctiveness of these marks one from another as an important feature of the invention; this ensures accuracy both in the purging and the subsequent inspection of the purged files, consonantly with the greatest speed.

In the drawings I have shown a set of five designs, A, B, C, D, E, as follows: A is a solid black block. B is a series of vertical

stripes. C is a series of heavy oblique stripes running from right to left. D is a series of dots. E is a series of oblique smaller stripes running from left to right. 5 Each of these conspicuous marks may be printed on the wrapper in the same ink along with the other matter thereon. Each of them extends over a sufficient vertical area, that wherever the wrapper is folded 10 its fold will traverse the mark and produce the same appearance at the fold. Each of these marks is so conspicuously different from any other that the eye instantly distinguishes it, although only a very narrow strip 15 along the fold is visible. This will be more apparent if two pieces of paper are laid on the drawings, having a slit or opening only one sixteenth of an inch wide and covering the marks. It will be seen that no difficulty 20 is encountered in instantly distinguishing them.

For further rapidity in operation, I locate each of the selected marks in a different position along the wrapper. While this 25 somewhat assists in distinguishing them from each other, its most important result is that it contributes great rapidity to the purging, because all of the marks on files to be purged will be aligned in a drawer and 30 they will arrange themselves however scattered, in definite visible ranks of distinctive and conspicuous marks, whereby the purging operation is much facilitated and its speed and accuracy increased.

35 In operation, each batch of papers relating to a particular transaction of a normal type is provided with one of the five wrappers folded over the top of the batch, as previously described. These wrappers are 40 applied, one during each purging period, which might be a month or two weeks or any other arbitrary period. Assuming the period to be one month, then by the time the E wrapper is applied the A wrappers 45 will be at least three and not more than four months old; thus beginning the day the E wrappers are applied the A wrappers are purged from the drawers and destroyed. The next month the A wrappers reappear 50 and the B wrappers are purged and so on. It is to be understood that in an exceedingly active business, or departments where normal transactions are closed more rapidly, the purging period may be reduced, as for instance, to three or even two weeks. The 55 purged files are placed on edge in trays and inspected by a supervisor.

The invention (a) effects a saving in operating costs by simplifying and speeding 60 up the purging operation and the inspection thereof. The purging operation in a large mail order house is a task of no small magnitude as may be appreciated when it is said that there may be more than a million 65 files to be purged each month. (b) The in-

vention effects a saving by its superior accuracy.

The invention further facilitates not only the removal from the drawers of all unnecessary files at the earliest possible moment, but through its speed and accuracy permits the purging period to be adjusted close to the safe limit; that is, to effect the accurate removal of all files, just as soon as they need no longer be kept. Quite aside 70 from the reduction in maintenance, housing, etc., of equipment (such as filing drawers,) this effects substantial economies in operation because it reduces to the lowest limit the number of files from which a desired one may be picked, and by reducing the number of the files it reduces the likelihood of error in selection between deceptively similar files (i.e., cases where name and initial are alike, etc.). Inaccuracy and delay produce floods of "complaint and adjustment" mail, which it is one of the main objects of operation to avoid. The invention in the several ways described 80 helps reduce such mail. It will be appreciated that small savings in time, and small improvements in accuracy, perhaps inconsiderable in other types of business, are of supreme importance in the mail order business, where an individual small item of 85 waste or economy is multiplied literally by millions.

I claim:

1. A purging system for files comprising in combination a succession of sets of wrappers, each adapted to be folded over and enclose the top edge of a file, designs comprising solid color, vertical stripes, oblique stripes and dots, applied to said sets of said wrappers across the line of fold therein, whereby from an inspection of the top of a file drawer, all files containing a particular design may be readily purged. 100

2. A purging system for files comprising in combination a succession of sets of wrappers, each adapted to be folded over and enclose the top edge of a file, designs comprising solid color, vertical stripes, oblique stripes and dots, applied to said sets of said wrappers across the line of fold therein, whereby from an inspection of the top of a file drawer, all files containing a particular design may be readily purged, said design of each type being arranged at a different place 105 along the line of the fold, whereby all said designs of the same type will be in alignment from front to rear of a drawer. 110

3. A purging system for files comprising in combination a succession of sets of wrappers, each adapted to be folded over and enclose the top edge of the file, a mark applied to the wrapper of each set and crossing the line of the fold therein, said mark being located at a different point along the 115 line of the fold in each set. 120

4. A purging system for file drawers, a wrapper adapted to be folded over the top edge of a file, a conspicuous mark applied to the wrapper across the line of the fold, in combination with a wrapper bearing a conspicuously different mark.
5. A purging system for files comprising in combination a succession of sets of wrappers, each adapted to be folded over and 10 enclose the top edge of a file, conspicuously different designs applied to the said sets of wrappers across the line of fold therein whereby from inspection of the top of the file drawer, all files containing a particular 15 design may be purged.
6. A purging device for a wrapper or the like, adapted to be folded over the top edge of a file, comprising a conspicuous mark on the wrapper, said mark arranged across the 20 normal line of fold and extending a sub-

stantial distance above and below the same, whereby substantial variations in the position of the fold line are accommodated and said line made to intersect said mark.

7. A purging device for a wrapper or the like, adapted to be folded over the top edge of a file, comprising a conspicuous mark on the wrapper, said mark arranged across the normal line of fold and extending a substantial distance above and below the same, 25 whereby substantial variations in the position of the fold line are accommodated and said line made to intersect said mark, said mark being so designed as to produce a uniform appearance along the line of fold 30 wherever the said line intersects the mark.

In witness whereof, I hereunto subscribe my name this 17th day of April, A. D., 1922.

PETER VAN VLissingen.
